The ornamental design for a golf accessory holder, as shown and described.

DESCRIPTION

FIG. 1 is a perspective view of a golf accessory holder showing my new design;
FIG. 2 is a top plan view thereof;
FIG. 3 is a rear elevational view thereof;
FIG. 4 is a left side elevation view thereof with the right side elevational view being a mirror image of that shown;
FIG. 5 is a front elevational view thereof; and,
FIG. 6 is a bottom plan view thereof.

The broken line showing of environment in the drawings is for illustrative purposes only and forms no part of the claimed design.
